US00D959270S

(12) **United States Design Patent** (10) **Patent No.:** **US D959,270 S**
Lee (45) **Date of Patent:** **** Aug. 2, 2022**

(54) **PACKAGING TRAY FOR CERAMIC SUBSTRATE**

(71) Applicant: **AMOGREENTECH CO., LTD.**, Gyeonggi-do (KR)

(72) Inventor: **Ji-Hyung Lee**, Gyeonggi-do (KR)

(73) Assignee: **AMOGREENTECH CO., LTD.**, Gyeonggi-do (KR)

(**) Term: **15 Years**

(21) Appl. No.: **29/738,445**

(22) Filed: **Jun. 17, 2020**

(30) **Foreign Application Priority Data**

Feb. 13, 2020 (KR) 30-2020-0006364

(51) **LOC (13) Cl.** **09-03**

(52) **U.S. Cl.**

USPC **D9/456**; D9/424

(58) **Field of Classification Search**

USPC D9/414, 516, 454, 456, 544, 690, 430, D9/434, 415, 424, 425, 428, 455, 737, D9/739, 751-755, 756, 760; D14/489; D23/269

CPC B65D 5/42; B65D 81/24; B65D 73/00; B65D 2577/10; B65D 5/48038

See application file for complete search history.

(57) **CLAIM**

The ornamental design for a packaging tray for ceramic substrate, as shown and described.

DESCRIPTION

FIG. 1 is a top perspective view;

FIG. 2 is a bottom perspective view;

FIG. 3 is a bottom view;

FIG. 4 is a top view;

FIG. 5 is a front view;

FIG. 6 is a back view;

FIG. 7 is a right side view; and,

FIG. 8 is a left side view.
